UNITED STATES PATENT OFFICE

BENJAMIN P. FINKBONE, OF MIDDLETOWN, OHIO, ASSIGNOR TO THE AMERICAN ROLLING MILL COMPANY, OF MIDDLETOWN, OHIO, A CORPORATION OF OHIO

METAL-COATING APPARATUS

Application filed December 30, 1926. Serial No. 158,079.

My invention relates to devices used for galvanizing or coating sheet metal with zinc and its alloys, and more particularly to coating with commercially pure zinc when alloyed with a substance which has a high tendency to develop dross, requires a higher temperature than normal galvanizing, and in addition has a high solvent action on the usual iron employed in the casting of galvanizing pots.

My invention relates also to diaphragms used in such metal coating devices for the purpose of preventing the materials at the exit side of the apparatus from getting into the flux box thereof.

As a brief description of the process which can be employed with advantage in my novel machine, a cleaned sheet of metal is passed through a flux, maintained at high temperature within a specially heated flux box, which flux will preferably be floated on a fairly thin layer of pure molten zinc. The flux may contain zinc ammonium chloride and ammonium chloride. In the main body of the pot, a body of molten lead will be maintained, through which the sheet passes from the flux box, and without the intervention of any rolls, passes under a dividing diaphragm in the pot and thence up through the lead where it encounters a floating body of molten zinc and aluminum, in which the aluminum is high enough in proportion to prevent development of spangle in the final product, say above three per cent, and preferably around eight per cent. Elements in the exit end of the pot keep up an agitation that maintains the zinc aluminum alloy in proper condition, and the sheet passes out between exit rolls, having a coating consisting of the zinc aluminum alloy upon its surface.

The objects of my invention are to eliminate as far as possible the danger of contamination of the coating material and cut down the loss due to deterioration of the container or pot; to provide a diaphragm separating the exit end from the entrance end of the pot to simplify and improve flux boxes in which added heat can be employed to avoid the overheating of the main lead

bath, and hence the coating materials at the exit of the pot, and still impart a proper fluxing temperature, and generally to provide a coating apparatus along the lines of a galvanizing device, but suitable for the application of pure zinc coatings and coatings of alloys of zinc, and alloys of zinc spelter, the latter being an alloy of zinc, lead, tin and other metals not refined out in the process of spelter production; also to provide for an effective agitation element in the form of stirring or skimming rolls, placing one on either side of the exit rolls. The object of these rolls being to keep the floating dross in as liquid a condition as possible and also to keep this dross, or other foreign substances, removed from the exit rolls. This being accomplished by having these stirring or skimming rolls placed very close to the exit rolls and traveling in the same direction as rolls nearest them.

I accomplish my objects by that certain construction and arrangement of parts to be hereinafter more specifically pointed out and claimed.

In the drawings:—

Figure 1 is a central vertical section taken through the device.

Figure 2 is a plan view of the exit end of the device.

Figure 3 is a detail of the flux box, with the parts separated.

I have not shown the brick work in which the pot is supported, nor the devices for heating the outside of the pot, and located within the brick work, since there is no difference between my device and regular devices in use in the industry today, in these particulars.

The pot 1 will be rectangular in shape and tapered toward the bottom, and may be formed as an iron casting of usual foundry stock. The entrance guides and rolls will not be of standard equipment. The flux box is formed of two side plates 3, welded to the two compartment ends. These ends, as indicated at 4 and 5, will be formed of plates having inturned base flanges 4a and 5a, to which are welded partition plates 4b and 5b, thus forming hol-

100

low boxes welded to the side plates, and hence closed at the sides, said boxes being thus open at the top for the insertion of electrical heating elements 6 and 7.

5 Standard guides 8 are illustrated, but not detailed, as they will not differ from the usual guiding devices in a galvanizing pot, except that there are no rolls at the low points of the guides, the pot being made 10 small enough that the sheet will reach to the exit rolls for feeding purposes, upon being fully inserted.

Welded into the pot, preferably centrally thereof, is a metal plate 9 serving as a separating wall or diaphragm, which extends 15 down to the guides, it being desirable to have the diaphragm as fully dividing the pot into two parts as the necessities of feeding the sheet through the bottom of the pot 20 will permit.

Welded into the exit side of the pot is an open shell 10, which is formed of nickel, chromium and iron alloy, in which the chromium will be around ten per cent or 25 above. This shell surrounds the portion of the pot in which the coating materials are floated on the sustaining bath.

The exit rolls are indicated at 11 and 12, the roll 11 being driven and having a worm 30 gear 13 thereon, which is driven by a worm 14. The several rolls and driving elements are held by frames 15, that are secured to the end of the pot and the partition or diaphragm. The worm shaft is driven by a 35 beveled gear drive 16, from a shaft 17 mounted across the top of the pot on suitable bearings 18.

The stirring rolls 19 and 20 extend across the pot as do the exit rolls, and are at the 40 same level, there being a beveled gear driven shaft 21 for each stirring roll, which rolls are driven by worm gears 22, as in the instance of the exit roll 11. The drives for the stirring rolls are located on the opposite side of the pot from the exit roll drive, and the arrangement is such that they turn in the same direction as the exit rolls near which they are located. In Figure 1 I have 45 shown by arrows the directions in which the exit rolls and the stirring rolls rotate.

Two weighted arms 23 are mounted on pivots at 24, and are equipped at their lower ends by shoes 25 which engage the spindles of the exit roll 12. This roll has a gear 55 26, driven from a gear 27 on the end of the exit roll 11, and lies in bearings 28 in the frames 15, which are wide enough to permit of lateral movement of the roll. The 60 teeth of the two gears will mesh within the range of movement of this roll 12, and thus the weighted arms control the pressure of the exit rolls on the sheet that is being fed thereby, and this arrangement avoids too 65 much squeezing when the rolls become fully

coated, and too little pressure or slippage when the rolls are cleaned.

The entire machine excepting the exit rolls are preferably formed of nickel, chromium alloy of iron that is employed for the 70 protective shell.

The operation of my device will not require description aside from the statement that the sheet passes down through the flux box through the guides to the exit rolls, and 75 that in the portion of the pot between the diaphragm and the exit end, there will be located a floating body of the coating material.

The flux box itself will be valuable where 80 it is desired in any instance to control the heat of the flux without substantially altering the heat in the main body of molten metal in a galvanizing device. In the particular process for which the device is used, 85 where some pure zinc is floated at the entrance end, the electrically heated flux box has been found quite useful.

It will be noted that to the least degree are materials permitted to get into the flux 90 box from the exit end of the device, and that rolls and driving parts are eliminated except where absolutely required, and the exit end of the structure.

Having thus described my invention, 95 what I claim as new and desire to secure by Letters Patent, is:—

1. A metal coating apparatus comprising a pot, having at its exit end an internal shell of an alloy of nickel, chromium and iron in which the chromium is at least 10 per cent to avoid solvent action with the coating material, and a partition between 100 said exit end of the pot and the remainder of the pot.

2. A metal coating apparatus comprising a pot, having at its exit end an internal shell of an alloy of nickel, chromium and iron in which the chromium is at least 10 per cent to avoid solvent action with the coating material, and a partition between 110 said exit end of the pot and the remainder of the pot, and extending to a point adjacent the base of the pot sufficient to permit a sheet to pass beneath it and above the 115 bottom of the pot.

3. A metal coating apparatus comprising a pot, having a partition dividing it into two parts, except for a space to permit the passage of a sheet beneath it, exit rolls and stirring or skimming rolls in the one part, and flux box in the other part, an internal shell of an alloy of nickel, chromium and iron in which the chromium is at least 10 per cent about said rolls within the pot to 120 avoid solvent action of coating material, and a flux box at the other end of the pot, having means for heating it additionally to the heat from the metal in the pot.

4. A metal coating apparatus comprising 125

- a pot, having a partition dividing it into two parts, except for a space to permit the passage of a sheet beneath it, exit rolls and stirring or skimming rolls in the one part, 5 and flux box in the other part, an internal shell of an alloy of nickel, chromium and iron in which the chromium is at least 10 per cent about said rolls within the pot to avoid solvent action of coating material, 10 and a flux box at the other end of the pot, having means for heating it additionally to the heat from the metal in the pot, said exit rolls being the only mode of feeding a sheet of metal that is located within the pot.
- 15 5. In a metal coating apparatus, a pot, and a flux box for said pot, said flux box having integral hollow walls, and means for applying heat within said hollow walls.
6. In a metal coating apparatus, a pot, 20 and a flux box for said pot, said flux box having integral hollow walls, and means for applying heat within said hollow walls, said heating means comprising electrical heating elements.
- 25 7. In a metal coating apparatus, a pot, and a flux box within the pot, said box formed of metal plates forming four walls thereof, one of said metal plates, at least, having an inturned base flange, and a partition plate secured to said flange and the 30 two side walls adjacent thereof, forming a hollow member as part of the wall of the box.
8. In a metal coating apparatus, a pot, 35 and a flux box within the pot, said box formed of metal plates forming four walls thereof, one of said metal plates, at least, having an inturned base flange, and a partition plate secured to said flange and the 40 two side walls adjacent thereof, forming a hollow member as part of the wall of the box, and an electrical heating element within said hollow member.

BENJAMIN P. FINKBONE.
